MACHINE FOR MAKING KNITTED FABRIC

Application filed March 13, 1931. Serial No. 522,450.

This invention relates to circular knitting machines and the method of operating same, and more particularly to circular knitting machines for making patterns in fabric by the wrapping of extra yarn around selected needles at each point where the pattern is desired.

One object of the invention is to produce a machine having complete selectivity as to the patterns which can be produced. It has heretofore been known to produce patterns by wrapping yarns around raised needles and for that purpose to cause striping yarn fingers to lay their yarns across the circle of needles and later to cross back inside the circle again. This invention relates to improved mechanism for varying the number of needles wrapped by the warms. The invention will be shown and described in a machine containing a plurality of pattern yarn fingers pivotally mounted to lay the wrapping yarns in front of selected needles.

In the drawings—

Fig. 1 is a front elevation of the head of a Scott and Williams circular knitting machine embodying the new invention, the view being taken partly in section through the middle of the machine;

Fig. 2 is a plan view of part of the head of the machine taken just above the latch ring on the line 2—2 of Fig. 1, showing the relation of the latch ring and the pattern yarn fingers;

Fig. 3 is a plan view of the head of the machine taken just below the upper bedplate on the line 3—3 of Fig. 1, showing the general coordination of the mechanism controlling the selection of the needles and the selection of the pattern yarn fingers;

Fig. 4 is an elevation of the left side of the machine and part of the head, showing the levers controlling the selection of the pattern yarn fingers and needles;

Fig. 4a is a front elevation on a reduced scale of the mechanism actuating the trick wheel idling plate;

Fig. 5 is a development of part of the inside of the latch ring showing the needles and yarns and the abutment in various relations;

Fig. 6 is a plan view of the mechanism shown in Fig. 5;

Figs. 7, 8 and 9 are vertical sections taken through the latch ring showing various lengths of pattern yarn fingers and their relation to the maintaining cam; Fig. 7 showing the long finger, Fig. 8 the medium finger and Fig. 9 the short finger;

Fig. 10 is a development similar to Fig. 5, showing the position of the yarn after the selected needles have gotten under the abutment, the arrow indicating the direction of movement of the needles;

Fig. 11 is a detail view in elevation of part of the lever system connecting the trick wheel to the striping yarn finger selecting cam;

Fig. 12 is a detail view in plan of the plate gear for racking the trick wheel and one end of the racking lever therefor shown in Fig. 3;

Fig. 13 is a plan view partly dotted in of the yarn furnishing take-ups on the bobbin stand; and

Fig. 14 is diagram showing the relations of the various kinds of yarn fingers to the maintaining cam.

The invention is shown embodied in the well known Scott and Williams seamless hosiery knitting machine having a revolving needle cylinder 260, such for instance as shown and described in the patent to Robert W. Scott, No. 1,152,850, dated September 7, 1915. The needle cylinder is controlled from a main pattern drum by a pattern chain, racked ahead intermittently by a pawl actuated from the driving pulley, all as shown in said Scott Patent No. 1,152,850.

The revolving needle cylinder 260 contains a circular series of vertically movable independent needles N, there being the usual sinkers with the sinker cam cap 300 and the usual knitting cams located below the throat plate 560 in the latch ring 550. This latch ring is pivotally mounted on a post 401 at the back of the machine as usual, and mounted on this latch ring is a bracket carrying a yarn bobbin stand 840 and the means supporting the pattern yarn fingers 766, 767, 768. The yarn bobbin stand and the pat-

tern yarn fingers revolve in unison with the needle cylinder by mechanism which will be described in detail a little later in the specification. The yarn bobbin stand also carries 5 the yarn take-up mechanism.

- In the example shown in the drawings the yarn fingers cross from the inside of the needle circle to the outside and thus lay the 10 yarns in front of selectively raised needles in order that an element having circumferential movement relatively to the needles may hold the yarns temporarily against the selected needles until they are taken by the latter, the yarn fingers meanwhile continuing 15 to revolve in unison with the needles. In the example shown in the drawings, this element having a circumferential movement relatively to the needles is a stationary abutment 870 on the latch ring 550 overlying the 20 needle circle and adapted to arrest each pattern yarn until it can be caught by the needles, and also adapted to release that yarn when the yarn finger snaps back across the needle circle to the inside of the circle. 25 It has heretofore been known to move such yarn fingers selectively out across the needle circle by cam action on their upper ends. In the example shown in the drawings, this selection of the yarn fingers is obtained by 30 having a plurality of butts on the upper ends of the yarn fingers and selecting the fingers by a vertically movable selector cam 750 whose movements are obtained from a trick wheel carried on the main bed-plate B 35 of the machine. This trick wheel also controls the vertical selection of the needles which distinguishes those to be wrapped from those which are not to be wrapped. According to this invention, the vertically 40 movable selector cam 750 which operates on the upper end of the pattern yarn fingers to cause selection for wrapping purposes, moves the lower end of the pattern yarn finger outside the needle circle but can release it to a maintaining cam before the 45 yarn has become engaged on the needles. The selector cam is made short in its circumferential dimension and the finger can be maintained with the lower end outside 50 the needle circle by a maintaining cam holding it after the release by the selector cam (Fig. 14). While this maintaining cam may be located with and move with the selector cam or independently, we prefer to mount 55 same in a stationary manner on the latch ring 550.

Bobbin stand

The bobbin stand 840 is mounted on the 60 upper bed-plate B' of the machine by means of a bracket 841 pivoted on the post 401 at the back of the machine (Figs. 1 and 2). The bracket is an open frame extending 65 over the top of the latch ring and needle cylinder and has an extension 842 on the

right side in which is mounted a connection from the vertical shaft 33 driven by the main bevel gear and drive shaft of the machine in the general manner shown in the patent to Robert W. Scott, No. 1,641,101, dated August 30, 1927. The drive shaft 33 preferably passes upward through the upper bed-plate B' further from the center of the machine than when it passes through the bobbin stand frame and it therefore has a universal joint connection 843 to a vertical stub shaft 844 in the bobbin stand frame extension 842. The bobbin stand proper 840 is revolved on the bobbin stand frame by a gear 846 on the upper end of this stub shaft meshing with a gear ring 847 screwed to the underside of the bobbin stand. On the upper side of the bobbin stand are cups 848 containing individual bobbins 850 of pattern yarn with their transparent protective tubes 849, as shown in Fig. 1. Revolving with the bobbin stand inside the bobbin stand frame is a sleeve 851, and axially located in this sleeve is a bobbin stand shaft 852 projecting vertically both above and below the bobbin stand frame. Above the bobbin stand the shaft projects upward beyond the tubes around the individual yarn bobbins to a level where the yarn take-up bracket is located. This take-up bracket 853 is fixed on the bobbin stand shaft and revolves with the bobbin stand. The yarn take-ups are of the pivoted arm type in which tension springs tend to maintain the tension on the yarn. The yarn is fed from the individual yarn bobbins to the usual tension discs 854 at the circumference of the take-up bracket, from there under a ring 855 to the long pivoted arm 856 with the 90 yarn take-up spring 857. Thence each yarn passes downwardly in a long individual tube 858 through the yarn take-up bracket and the bobbin stand sleeve until the yarns emerge a short distance above the latch ring 550. Near the point of emergence of the 95 yarn from these individual tubes and carried by the bobbin stand shaft is a slotted pattern yarn finger ring 860 revolving with the bobbin stand and in which the pattern 100 yarn fingers 766, 767 and 768 are carried.

For the purpose of assisting in drawing the yarns, pattern yarn furnishing means are provided which cause the pivoted arm 856 of the yarn take-ups to draw from the bobbins 850 through the tension discs 854 enough yarn to wrap the selected needles and keep it under the tension of the take-up 105 spring 857 until required. This means comprises a tail 758 on each take-up arm 856 and a yarn-furnishing cam 760 on a post 761 projecting upwardly from the bracket 841 at the rear of the machine opposite the throat plate 560. The cam 760 lies in the path of the tails 758 and as the latter revolve they are pressed down under the cam and measure 110 115 120 125 130

off into the take-up the yarn needed for the widest wrap pattern in the stocking. The lowest point of the cam 760 is opposite the post 761 on which it is mounted and therefore opposite the post 401 and the throat plate 560 (Figs. 2 and 13). In Fig. 2 the knocking over point is indicated by the short arrow to the left of the throat plate pointing toward the center of the machine and it will therefore be noted that the yarn is drawn from the bobbin and the tension discs before the stitch is drawn. Therefore the only tension in drawing the stitch is that required to pull down the take-up. As a result the wrap yarn is fed at high speed without puckering of the fabric due to extra tension on the wrap yarns. If the pattern for any yarn is not that required for some other finger, the take-up will hold the surplus and simply not draw so much yarn on the next revolution. The portion of the cam between the post 761 and the knocking over point is an upturned end 762 to guide the tails 758 under the cam when on the reverse stroke during reciprocation. Thus the yarn furnishing cooperates with the varied wrap movements of the yarn fingers to produce a perfect product with varied stripes.

30 *Needle selection for patterning*

There is the usual needle cylinder revolving in counter-clockwise direction as the machine appears in Fig. 2, having needles elevated and depressed by the conventional knitting cams (not shown). In addition to such knitting cams there are provided special cams—which will be described later—for selecting those needles which are to take the wrapping yarns. This selection of needles is made by any desired mechanism but in the drawings we have indicated their selection by a trick wheel 800 on the lower bed-plate B and jacks lying in slots in the needle cylinder underneath the needles N. The trick wheel may be racked once every four revolutions of the needle cylinder by lever means driven from the so-called plate gear 65 (Fig. 12) in a manner similar to the mechanism shown in the patent to Robert W. Scott, No. 1,311,623, dated July 29, 1919. These racking lever means include a racking lever 801, a toggle link 802 pivoted on the lower bed-plate B and a pawl 803 engaging teeth 804 at the bottom of the trick wheel 800 (Figs. 12 and 3). There is a tension spring 805 between the pawl lever and the lower bed-plate B tending to hold the pawl in contact with the teeth on the trick wheel. The end of the spring 805 toward the trick wheel is on the bed-plate. The pawl is adapted to rack the trick wheel forward one tooth in a counter-clockwise direction every time the pawl is retracted.

The trick wheel 800 is a vertical cylinder mounted on the lower bed-plate B near the

front of the machine, and it has a series of vertical slots around its circumference in which lie pattern jacks 810 having a series of butts at a plurality of levels which can be broken off as required to produce the necessary pattern in the well-known manner. The slots in which the jacks 810 are carried are spaced apart a distance equal to the length of one of the teeth 804 so that each rack caused by the pawl will advance the trick wheel from one pattern jack to the next. This trick wheel is adapted to carry the pattern indications for both the needles and the pattern yarn fingers, the lower part of the trick wheel being adapted to take care of the needles and the upper part of the trick wheel moving the vertical selector cam 750 for the pattern yarn fingers. As shown in Figure 4, we use spring bands 807 to hold the pattern jacks in the trick wheel 800.

The pattern indications on the trick wheel 800 for the cylinder needles are transmitted to the cylinder by means of jacks 736 in slots in the needle cylinder through the intermediary of a plurality of needle reader cams 90 820 mounted one above the other on a vertical pin 821 (Fig. 3). There is a reader cam for each level of butts corresponding to the portion of the trick wheel furnishing selections for the needles and each reader cam furnishing selections for the needles has a nose 822 adapted to contact with butts on a cylinder jack. These cylinder jacks are adapted to be selected and raised, and in turn to raise the cylinder needles in a manner similar to that shown in the patent to Ivan W. Grothey No. 1,678,385, on July 24, 1928. In the arrangement shown in the drawings the reading tail 823 of the reader cams for the cylinder jacks 736 and their 100 associated needles are so located that when one of the butts on a pattern jack 810 comes opposite the reading tail, the nose of that reader cam will not engage against the projecting butt on any of the cylinder jacks 736 110 but will allow those butts to pass freely. Thus, if it is desired to select a needle for wrapping purposes from a certain cylinder jack butt level, there should be no butt on the trick wheel at that level. The cylinder 115 jacks of the needles which are to be wrapped do not have butts at that level. To maintain the reader cams with their noses in contact with the butts on the cylinder jacks and the reading tails in contact with the butts on the pattern jacks, tension springs 824 are fastened to extensions of the reading tails, these tension springs being held by a vertical post 826 on the lower bed-plate B of the machine.

The design which it is desired to wrap is laid out on the cylinder jacks 736 by knocking off butts, a butt missing meaning that the needle is to be selectively raised for wrapping and a separate level of butts be- 130

ing set aside for each desired combination during any one course or revolution of the machine. There are as many butt levels on the portion of the trick wheel for the cylinder jacks as there are butt levels on the cylinder jacks. When the cam or cams on the plate gear 65 are adjusted to rack the trick wheel once every four revolutions, each jack in the trick wheel makes it possible to select a different combination of needles for each four courses of knitting and if the cams on the plate gear 65 are set to rack the trick wheel every two revolutions, the selections of needles for wrapping may be changed every two revolutions. Further variations in pattern are obtainable by having a plurality of butts missing on the same pattern jack or jacks 810 in the trick wheel. This means that several of the reader cams are in action simultaneously, with the result that a plurality of combinations of selective needles set up on the cylinder jacks may be raised in the needle cylinder at the same time. This combining of the selections set up in the different levels of butts on the cylinder jacks may be further varied by throwing groups of reader cams out of action from the main pattern drum. To control this throwing out of action of groups of reader cams the following mechanism is provided:

Each needle reader cam 820 has an extension extending horizontally on the opposite side of the post 821 from the nose 822 and the cams are adapted to be tipped out of operative contact with the trick wheel jacks in groups by a plurality of idling levers 829. In the drawings we have shown two idling levers 829 each controlling a group of needle reader cams. The idling levers are actuated from the main pattern drum 120 by pull wires 830, 830' and pivoted bell crank levers or thrust rods 831, 831'. The lower group of needle reader cams is shown controlled by the lower pull wire 830 (Fig. 4) and the outer thrust rod 831.

Pattern yarn finger selecting mechanism

Turning now to the connections for transmitting indications from the trick wheel to pattern yarn fingers for the purpose of varying the color of the yarn on a particular group of needles from course to course, mechanism shown in Figs. 3 and 4 is employed. There are two reader cams 825' and 825 which have no noses 822 near the cylinder jacks (Fig. 4) but the rod on which the vertically movable selecting cam 750 rests is connected to each of these reader cams in the yarn finger or yarn color group by a linkage which includes a rock shaft 832 or rock shaft sleeve 833 located at the back of the machine and extending from the left side of the machine where the reader

cams are located to the vertical rod 754 underneath the vertically movable selector cam 750 on the right side of the machine.

The connection from top finger reader cam 825' is by a long link 834' to a short lever 872 on the left end of the rock shaft sleeve 833 and a lever 838 from the right end of the sleeve to the lower end of the vertical pin 754. The connection from the lower finger reader cam 825 is by a long link 834 to a short link 873 on the left end of the rock shaft 832 and a lever 839 from the right end of the shaft to the lower end of the vertical pin 754. As shown in Fig. 11 there is a tension spring 845 attached to the lever 838 tending to hold the vertical pin 754 in its uppermost position. The finger selector cam 750 therefore can be controlled from either reader cam 825' or 825 or both as desired. When the reading tail 823 of one of these cams rests on the surface of the trick wheel drum 800 the selector cam 750 is opposite the highest butt level of the pattern yarn fingers, when the tail 823 rests on a short i. e., low but on a trick wheel jack 810 the cam 750 is opposite the middle butt level or the pattern yarn fingers, and when the tail 823 rests on a long i. e., high butt the selector cam is opposite the lowest of the three pattern yarn finger butt levels. When the finger reader cams 825' and 825 are withdrawn completely from contact with the trick wheel by mechanism which is described in the next paragraph, the selector cam 750 is lowered to the level of the space below the three butt levels of the fingers and there being no butts at this level the fingers are not swung across the needle circle.

The two pattern yarn finger reader cams 825', 825 are thrown out of action by the movements of the bell crank levers 831', 831 which throw the groups of needle reader cams out of action. To throw out the finger reader cam 825' there is a screw carried by the upper idling lever 829 which lies in line with the cam 825' and the movement of the idling lever 829 to bring its group of reader cams to idle position, forces the screw 827 against the cam 825' and withdraws it from contact with the trick wheel as shown in Fig. 3. This movement also swings the lever 839 under the vertical pin 754 to its lowermost position. The finger reader cam 825 is thrown out of operative relation with the trick wheel by means of a stop 835 on the pull wire 830. This stop takes against a depending lower end of the short lever 873 and pulls the long link 834 toward the rear of the machine when the bell crank lever 831 swings to the rear.

It should be noted that in this machine it is possible in changing from one yarn to another for wrapping the same part of the circle, to change the length of "dwell" of

the yarn across the needle circle by using fingers of different lengths.

Pattern yarn feeding mechanism

- 5 The machine contains the usual latch ring with yarn fingers F therein located in the throat plate for feeding the body yarns, these yarn fingers being pivotally mounted in the usual manner to raise the yarns out of 70
- 10 action. As already mentioned, the pattern or wrap yarns are fed to the needles through eyes 759 in pattern yarn fingers 766, 767, 768 mounted on horizontal pivots 859 and set in slots in a pattern yarn finger ring 860 75
- 15 revolving with and carried under the pattern yarn bobbin stand by the sleeve 851. The yarn fingers are held in the slots in the ring by a spring band 769 and also a separate tension spring 815 for each finger 80
- 20 (Fig. 1). The tension springs are located just below the yarn finger ring 860 and are fastened to the tubes 858 and the fingers are adapted to swing pivotally outward across the needle circle. The normal position of 85
- 25 these fingers, in the example shown in the drawings, is with the lower or feeding ends of the pattern yarn fingers inside the needle circle. The yarn fingers are adapted to be swung radially outward across the needle 90
- 30 circle for the purpose of feeding the yarn to the needles by means of the above-mentioned selector cam 750 shown in Fig. 1, this vertically movable cam being mounted on a sleeve 751 which sleeve is vertically 95
- 35 movable on a stationary pin 752 depending from the stationary frame of the bobbin stand. There is a tension spring between the sleeve 751 and the stationary depending pin 752 tending to keep the vertical reader 100
- 40 cam 750 in its lowermost position and there is an auxiliary guide pin 756 which passes through the reader cam itself, thus preventing the sleeve 751 from turning on the depending pin 752. There is a lug 753 projecting laterally from the sleeve 751 and overlying the upper end of a vertical pin 105
- 45 754 which brings the pattern indications from the trick wheel. This vertical pin 754 is guided by a bracket 755 carried by the 110
- 50 support for the driving mechanism of the bobbin stand. There are a plurality of positions for butts 757 on the upper end of each yarn finger, thus making it possible to select as between the fingers which of them shall 115
- 55 be moved radially outward, the presence of the reader cam 750 opposite a butt 757 meaning that the lower or feeding end of the yarn finger will be moved radially outward across the needle circle, as shown at 120
- 60 the right side of Fig. 1. The pattern yarn finger ring 860 revolves in unison with the needles and the relative movement of the yarn around the needles is obtained by means of another element. An example of 125
- 65 such element will be described next.
- As shown in the drawings, this element consists of a stop or abutment fixed on the latch ring and extending across the needle circle at a distance from the main yarn feeding point and adapted to carry each pattern yarn into contact with the selected needles as the relative rotation between the needles and the knitting cams takes place. This abutment is shown as a plate 870 adjustably screwed on the top of the latch ring 550 and having a hook or inverted U end fitting over the hooks of the needles at the desired point in the circle, as shown in Figs. 8 and 9, and leaving a space through which the selected needles move when taking a pattern yarn. The downwardly bent inner end or side 871 or the U on the inside of the needle circle extends circumferentially forward in the direction of movement of the needle cylinder and the side of the abutment 85
- on which the needles and yarns approach is bevelled back slightly inside the needle circle in order to permit the yarn to slide off the abutment at the proper time (Fig. 10). As can be seen from an examination 90
- of Fig. 8 or Fig. 9, when the yarn is laid across the circle in front of the abutment it lies across the shank of the needle from the inside of the circle to the outside of the circle just below the hooks of the selected 95
- needles. This can be seen in Figs. 5 and 6, where the yarn y' is shown just after having been laid across the abutment from the previous wrapping of the pattern figure p-1. Fig. 6 is a typical plan view of any of 100
- the wrapping yarns at such a time. The needles will radially engage the yarn as they pass under the hook of the abutment. A subsequent position of the yarn can be seen in Fig. 10 where the group of selected 105
- needles can be seen approaching the throat plate 560. The position of yarn y' after the yarn finger is returned across the needle circle to the inside is similar to the position of the yarn of the pattern figures p-2 and p-3 in Fig. 5.
- For the purpose of permitting the striping or pattern yarn to enter only the selected needles and to prevent it entering needles not selected, a guard or apron 20 is mounted 110
- inside the needle circle (Fig. 2). This guard is shown as a segmental ring or apron beginning before the knocking over point and ending at a point after the beginning of the abutment 870 (see Figs. 2, 5 and 10). The end of the guard near the throat plate terminates in a wire 21 connected to the latch ring. The upper edge of this ring is formed as a guard with certain parts high enough to hold the pattern yarn above the 115
- needles not specially elevated to take the wrapping yarns.
- It is desirable of course to have complete selectivity as to the needles which are to be wrapped and certain difficulties have 120
- 125
- 130

heretofore arisen on this point in machines of this type. Thus it has been noticed that in order to wrap a large group of needles, it has heretofore been necessary to make the selector cam 750 with a rather long contact face for the butts on the pattern yarn fingers. With such a construction a considerable space between the butts 757 on the fingers must be allowed for changing the cam from one level to another, and during this time a number of needles are passing the cam which cannot be wrapped. It is one object of this invention to minimize these "blind" spots. Assuming, for example, that the patterns being made are vertical patterns, such as shown for instance in Fig. 5, it has heretofore been customary to make the selector cam of sufficient length to wrap the widest pattern $p-1$ and therefore necessarily all pattern fingers would be held out for the same length of time. Thus the selector cam was set to hold the fingers for intervals corresponding to, say, twenty needles. This necessitated such a long face on the cam that it was impossible to get as many patterns or stripes in the stocking as desired and those stripes could not always be placed at the desired point. Thus with the long face reader cam such as would heretofore have been necessary to produce a stripe like the wide clocking stripe $p-1$, it was necessary to allow so much blind space before and after the stripe that the two neighboring stripes could not both be brought reasonably near. It has been discovered that this can be avoided by dividing the work of holding the yarn finger out across the needle circle between the selector cam and a maintaining cam which holds the yarn finger outside the needle circle after the selector cam has released it. The face of the selector cam is made shorter than heretofore. Thus it is possible to move the selector cam to a new level before the first selected yarn fingers are allowed to snap back across to the inside of the needle circle. This minimizes the dead spots and permits yarn fingers to lay yarns across the needle circle in close juxtaposition to each other in adjacent panels or groupings.

This maintaining cam preferably does not act on the upper end of the yarn finger but is mounted on the latch ring as shown at 763, in the drawings. As can be seen clearly in Figs. 1 and 2, this maintaining cam 763 is screwed to the upper surface of the latch ring adjacent the abutment 870 in such a position that the yarn finger will come opposite it circumferentially about the time that the finger reaches the abutment in its counter-clockwise movement, and the cam is of such a length as to come to an end before the knocking over point. In its simplest form this maintaining cam has an upstanding edge against the outside of

which the lower end of the yarn fingers ride, thus holding the lower or feeding end of the yarn fingers outside the needle circle until the finger passes beyond the cam. If desired, of course it is possible to have yarn fingers of different lengths making some of them long enough to depend vertically until their lower ends are opposite and will be engaged by this maintaining cam, such, for instance, as shown in Figs. 7 and 8, while others may be made shorter, as shown in Fig. 9, and not engage the cam at all. These latter yarn fingers will snap back across the needle circle as soon as it has passed beyond the selecting cam 750. The eye 769 through which the yarn passes may be the same distance above the latch ring no matter what the length of the finger.

We have further discovered that an additional distinction can be made and the maintaining cam means adapted to act with still greater selectivity by having the maintaining cam stepped, with its tail or end portion 765, i. e., the end nearest the knocking over point, lower than the end 764 which engages the finger first. Such a construction is shown in the drawings. To make use of this step in a selective manner, the yarn fingers which are long enough to engage the maintaining cam are of varied length. The fingers 766 are long enough to remain in contact with the maintaining cam after they have passed the step. The intermediate length fingers 767 are of a length which will permit them to snap back across the circle when the finger passes the step and goes from the high part 764 to the low part 765 of the cam. The short fingers which do not engage the maintaining cam at all are numbered 768. In Fig. 14 is shown the relations of the upper and lower ends of the various kinds of striping yarn fingers to the selecting cam 750 and maintaining cam 763 at various points. In Fig. 7 is shown a long finger 766 before the butt on the upper end of the finger has ridden off the selecting cam 750 and allowed the tip of the finger to fall against the maintaining cam. The finger 766 is approximately in the position of the finger shown in Fig. 6. The intermediate length of finger 767 is shown in section in Fig. 8 after its release by the selecting cam but while the finger is resting against the high part 764 of the maintaining cam. In Fig. 10 is shown in side elevation the position of an intermediate length finger 767 shortly before it reaches the end of the high surface 764 of the cam, the yarn at this point having been drawn under the hooks of the group of selected needles, but the yarn finger not yet having snapped back across to the inside of the circle. The horizontal arrow in this figure indicates the direction of movement of the needles and striping yarn fingers. The short finger 768

which is not long enough to reach the maintaining cam at all, is shown in Fig. 9 and Fig. 5, it being shown in Fig. 9 before it is snapped back to the inside of the needle circle and on the left in Fig. 5 after it is snapped back across the circle. In Fig. 6 the final position of the yarn after the wrapping but before the knocking over, is indicated in the central pair of selected needles, n^2 i. e., those below the tail 871 of the abutment and corresponding to the stripe $p-2$ of Fig. 5. Thus the selector cam is employed to push the fingers out to lay the yarns in front of the abutment and the maintaining cams are used to hold the pattern yarn fingers out until all the pattern needles have passed. This gives an accurate and controlled release of the yarn fingers so that they may be snapped back to the inside of the needle circle by the spring 815 on the plate 860. It should be noted that these forms of selectivity of the invention permit yarn fingers which are feeding yarn to a small group of needles to snap back across the circle before the time for the next finger to come out has arrived—thus avoiding any possibility of the yarn in the second finger being laid across the needle circle and coming into engagement with the abutment before the first yarn has been taken off the abutment by the snapping of the first yarn finger back to the inside of the needle circle. This is of great practical advantage because it has been found that if the second yarn comes into engagement with the abutment before the first yarn leaves it, the first yarn will be caught and held on the abutment longer than desired and if the second group of selected needles comes up to the abutment within a sufficiently short period of time, both yarns will be wrapped around the second group of selected needles. This feature, while a disadvantage with certain patterns, may be turned to advantage to produce still another design by allowing the second yarn to catch the first yarn, arranging the pattern accordingly.

In the machine shown in the drawings, the ring which carries the yarn fingers is slotted with, say, eighty slots to permit yarn fingers to be located or concentrated at any desired point but it is not ordinarily intended to use all the slots at once. Thus, as shown in the drawings, some of the yarn fingers are located in pairs in adjacent slots with a number of slots vacant before the next pair and there is a pair of fingers at the leading end of each panel or segment of the needle circle where it is desired to have a stripe such as $p-1$, $p-2$ or $p-3$. In the machine shown in the drawings there are sixteen panels, a number which would be quite impossible with the variation in widths and locations of panels indicated, for

instance, by the patterns p' , p^2 and p^3 in Fig. 5, if it were not for this invention.

Underneath the rack wheel teeth 804 is a pivotally mounted idling plate 812 having thereon surfaces which do not project radially beyond the rack wheel teeth and other surfaces which do project. One surface on this plate 814 projects beyond the teeth far enough to push the pawl 803 back out of contact with all the teeth 804, thus causing the pawl to idle back and forth without turning the rack wheel. Another surface 813 on this plate pushes the pawl away from the rack wheel sufficiently to be out of the path of the low tooth 804' and not enough to be out of the path of the remainder of the teeth 804. It will therefore be obvious that when this intermediate surface engages the pawl the trick wheel will revolve until the pawl reaches the low tooth. This low tooth designates the beginning of the pattern of the stocking and therefore, when the rack wheel ceases to revolve while the pawl idles over the low tooth, the rack wheel is ready to begin the pattern of the stocking. The high surface 814 which disengages the pawl from all the teeth 804 suspends the patterning during the heel of the stocking no matter at what point the patterning may be.

The mechanism operating this plate may be of any desired kind, it being necessary merely to provide means for pivoting the plate about the center of the trick wheel sufficiently to bring these various surfaces into line with the end of the pawl, but in the drawing we have shown the bell crank lever connection running to the disc cam 816 on the shaft 80 which carries the drive gear 122 for the pattern drum 120 (Fig. 4a). Such a use of this shaft is shown in the patent to E. E. Paquette, No. 1,723,881, dated August 6th, 1929.

Operation of machine

The construction of the machine having been set forth, we will now describe its operation. We shall assume, in this description, that the machine has reached a portion in the stocking where it is ready to begin making a wrapped or embroidery stitch pattern. Up to this time the wrapping mechanism has been idle. The pawl 803 has been idling back and forth over the low tooth 804' of the series of trick wheel teeth 804, being held from engagement with the low tooth by the intermediate surface 813 and the idling plate 812. The reader cams 820, 825, 825' for the needle selecting and the pattern yarn finger (i. e., color) selecting are held disengaged from the trick wheel 800 by means of the thrust rods 831 and 831' which are in their extreme left positions as they appear in Fig. 4. In this position the pull wire 830 on the thrust rod 831 turns

the lowermost idling lever 829 counter-clockwise and holds the cam 825 radially inward. In this position the reading tails 823 of this group of needle selecting cams are beyond the range of the butts on the jacks 810 in the trick wheel. When in this left position, the thrust rod 831 holds the short link 873 to the left by virtue of the stop 835, and the long link 834 connected to the short link 873 pulls the lower of the two pattern yarn finger or color selecting cams radially inward so that its reading tail 823 is also beyond the range of the butts on the jacks 810 in the trick wheel. When the short link 873, just mentioned, is in its left position the rock shaft holds the lever 839 in its lowermost position. While the thrust rod 831' is in its extreme left position the pull wire 830' holds the upper of the two idling levers 829 in its dotted line position shown in Fig. 3 with the tails 823 of the upper group of needle reader cams held out of operative relation with the jacks on the trick wheel. This upper idling lever 829 carries the screw 827 (see Figs. 3 and 4) and when the lever 829 is swung to the position shown in Fig. 3 the screw therefore pushes radially inward the uppermost finger or color reader cam 825' to the position shown in Fig. 3. The idling lever 829 is itself actually below the extreme end of the tails of the two finger or color reader cams and, therefore, does not contact with those tails directly. The pushing of the uppermost finger or color reader cam 825' to inoperative position by the screw 827 also serves to move the long line 834' and the short lever 872 in such manner as to turn the rock shaft 833 and lower the lever 838, the pin 754 and the sleeve 751. As a result under the influence of gravity, the pattern yarn finger selecting cam 750 drops to its lowermost position where it is opposite the gap underneath the three selecting butts on the upper ends of the yarn fingers. In addition to holding the parts in positions already mentioned in connection therewith the thrust rod when in its extreme left position also serves to hold the lower of the two finger reader cams out of operative relation with the trick wheel jacks 810. This is accomplished through the stop 835, short lever 873 and long lever 834, connecting the short link 873 with the lower of the two reader cams for the pattern selecting fingers.

The patterning is commenced by a rack on the main pattern drum which releases one or both of the thrust rods 831, 831' from their extreme left position, turning the idling levers 829 to release the needle reader cams 820 and through the stop 835 and levers 834 and 834' by means of the springs 824 also bringing one or both of the reader cams for the pattern selecting fingers into operative relation with the trick wheel.

This same rack also serves to turn the idling plate 812 till no surface is opposite the pawl 803 with the result that the spring 805 brings the pawl into engagement with the low tooth 804' and the trick wheel begins to rack and bring the pattern selections of the trick wheel jacks 810 under the reading tails 823, the pattern yarn finger and needle reader cams 820. When any of the needle reader cams reaches a point on the trick wheel where a butt is missing from one of the jacks 810 it drops against the surface of the trick wheel proper and its nose 822 presses radially inward against the butts of the cylinder jacks 736. This brings the cylinder jack in line with the raising cam (not shown) which raises the jack and needle to selective level in the well known manner.

This same rack on the trick wheel brings under the color reader cams 825, 825' a high butt, low butt or no butt on jack 810, and, according to which it is, the rock shaft 832 and the rock shaft sleeve 833 raise the vertical pin 754, the sleeve 751 and the selector cam 750 to bring the latter opposite the lowermost, middle or uppermost butt level on the yarn fingers, respectively. The selection of the yarn fingers thereupon takes place in accordance with the butts on the yarn fingers 766, 767 and 768. As each yarn finger comes around to and contacts with the selector cam 750 it will assume its various positions as shown in Fig. 14, its lower end being pushed radially downward across the needle circle until its lower end lies radially outside both the abutment 870 and the maintaining cam 763. This lays the yarn in front of the abutment and, as the pattern yarn fingers continue to revolve in unison with the needle circle, the yarn catches against the abutment and is held there until engaged by the selected needles of its group. If the particular group is very small—and is to remain small throughout the entire stocking—the yarn will be fed from one of the short fingers 768 and when the butt on the upper end of the finger reaches the end of the selecting cam 750 the finger is released and snaps back across the top of the high part 764 of the maintaining cam to the inside of the circle of needles under the influence of its spring band 769 and tension spring 815. This will draw the yarn back across to the inside of the needle circle behind the selected group of needles, such, for instance, as group n^2 of Fig. 5, thus completing the wrapping. If the group of needles is somewhat larger, as, for instance, the group making the figure p^1 shown in Fig. 5, a medium length yarn finger 767 may be used to feed the yarn. In this case the finger will not return across the needle circle to the inside until the continued revolution of the yarn finger ring 130

860 brings the lower end of the yarn finger beyond the high part 764 of the maintaining cam 763 to the low part 765. The finger then snaps back over the top of the low part 765 taking the yarn with it as in the previous case. If the group of needles to be wrapped is still larger, a long finger 766 may be used in which case the finger will not snap back across the needle circle until it reaches the end of the low part 765 of the maintaining cam nearest the throat plate. The varying amount of pattern yarns required for wrapping these groups of greatly different sizes is obtained automatically from the take-ups as needed as follows: Prior to the time that the yarn finger for any selected group of needles reaches the knocking over point the tail 758 of its take-up arm 856 passes under the yarn measuring cam 760, raising the arm 856 and drawing the maximum amount of yarn necessary to wrap any one of the groups of needles to be selected in the pattern set up on the lower part of the trick wheel. The measuring cam having drawn this maximum amount from the bobbin 850 through the tension discs 854 the yarn can be delivered to the needles rapidly and under the tension solely of the tension spring 857 of the take-up rapidly and without deformation of the fabric being knit. If the particular group being wrapped is not of the maximum size, the unused yarn will remain in the take-up and the correspondingly lesser amount of yarn will be drawn on the next revolution when the tail 758 of the take-up goes under the yarn measuring cam 760. When the selection of yarn fingers is to be changed the racking of the trick wheel 800 will bring butts of different height under the reading tails 823 of the finger reading cams and the rock shaft and vertical pin 754 will bring the selector cam 750 to a new butt level. Since the selector cam 750 need hold the lower ends of the yarn fingers radially upward across the needle circle only for a short period of time until they move to a position opposite the maintaining cam 763, the operative face of the selector cam 750 is comparatively short and it can be changed from one level to another without requiring too great separation of the yarn fingers in the ring 860 to permit it to make the change. It obviously is one of the advantages of the invention that a great many patterns can be put in the stocking of varied width with yarn changes from course to course in the same wales without unnecessary spacing between the patterns or figures.

If desired, the patterns set up on the trick wheel can be so arranged that by alteration in operative position of the two pattern yarn finger reading cams a sequence of selections for the pattern yarn fingers can be obtained which is double the number of

jacks in the trick wheel. Similarly, if desired, two different series or sequences of selections of needles can be set up in the trick wheel totalling in number twice the number of the jacks in the trick wheel, this being obtained by using the idling levers 829 in alternation. A greater number of idling levers or pattern yarn finger reader cams can be used, if desired, to obtain still greater lengths of patterns.

It will be obvious that many variations will occur to those skilled in the art, which lie within the scope of our invention.

We claim:

1. A knitting machine having a circle of independent needles, means for selecting needles for wrapping, pattern yarn fingers and finger selecting means adapted to cause a finger to lay a pattern yarn in front of a selected needle or needles in combination with means selecting and holding across the needle circle after said finger selecting means have released same, certain of the fingers chosen by the finger selecting means, for the purpose of varying the length of wrap.

2. In a knitting machine having a circle of independent needles, means for selecting needles for wrapping and pattern yarn fingers adapted to lay yarns across the needle circle for wrapping purposes in combination with cam means adapted to maintain certain of the fingers across the needle circle after the yarns are laid across the circle, to give different lengths of dwell across the needle circle according to the number of needles to be wrapped.

3. A circular knitting machine having independent needles, means for raising needles selectively, a pattern yarn finger, finger selecting means adapted to cause said finger to lay a pattern yarn in front of a needle or needles raised by said needle selecting means, an element having circumferential movement relatively to the needles and adapted temporarily to hold against said raised needles the pattern yarn laid in front of them, in combination with means maintaining the yarn in front of the selected needles after release of the finger by the finger selecting means.

4. A circular knitting machine having a circle of independent needles, means for raising needles selectively, and pattern yarn fingers adapted to lay yarn across the needle circle for wrapping purposes in combination with an element having circumferential movement relatively to the needles and adapted temporarily to hold against said raised needles the pattern yarn laid in front of them, and cam means adapted to give the fingers different lengths of dwell across the needle circle according to the number of needles to be wrapped.

5. A circular knitting machine having a

circle of independent needles, means for raising needles selectively, a yarn finger adapted to lay a wrapping yarn in front of a needle or needles raised by said needle 5 selecting means, and an element having circumferential movement relatively to the needles and adapted to wrap on said selected needles the pattern yarn laid in front of them, in combination with finger selecting 10 means adapted to cause said finger to lay the pattern yarn in front of the selected needles, and other means adapted to maintain said finger in the position given it by the finger selecting means after its release 15 by the latter.

6. A circular knitting machine having a rotary circle of independent needles, means for selectively raising said needles and a plurality of pattern yarn fingers pivotally 20 supported above the needles, means for rotating said fingers in unison with the needles, in combination with finger selecting means adapted to cause the feeding ends of said fingers to lay pattern yarns in front of 25 needles thus selected at a point on the needle circle different from the main yarn feed, and a maintaining cam adapted to act on the lower end of certain of the fingers chosen by the finger selecting means and maintaining 30 same outside the needle circle for a longer length of travel.

7. A circular knitting machine having a rotary circle of independent needles, means for raising a selection of needles at a point 35 on the needle circle different from the main yarn feed, a main yarn feed, a plurality of pattern yarn fingers whose feeding ends are of different lengths, in combination with selecting means adapted to cause the feeding 40 ends of said fingers to lay the yarn across the needle circle, a stationary abutment adapted to engage the yarns thus laid across the circle and to cause them to be wrapped, and a maintaining cam adapted to 45 hold the feeding ends of the longer of said fingers in the position given it by the selecting means after they have reached said abutment.

8. A circular knitting machine having a 50 revolving needle cylinder, independent needles in said cylinder, a main yarn finger and a plurality of pattern yarn fingers pivotally mounted above said cylinder, revolving in unison therewith and adapted to vibrate 55 across said circle of needles for the purpose of laying wrapping yarns across said circle, means adapted to raise needles selectively to engage said pattern yarns, an apron adapted to prevent yarns from said pattern fingers 60 coming into engagement with needles not selected, means selecting yarn fingers to lay across the circle, some of said yarn fingers being longer than others, in combination with a stationary maintaining cam located 65 at a point on the needle circle different from

that of the main yarn finger, adapted to act selectively on said yarn fingers to vary the length of time that said yarn fingers remain across the needle circle.

9. A circular knitting machine having a 70 revolving needle cylinder, independent needles vertically movable in said cylinder, means for raising said needles selectively for pattern purposes, pattern yarn fingers adapted to lay yarns across the needle circle by movement from the inside to the outside thereof, said yarn fingers rotating with said needles, a stationary abutment adapted to lie in the path of and arrest the pattern yarns thus laid across the circle, in combination with a stationary cam located adjacent the 75 said abutment adapted to hold outside the needle circle for a definite period of time, fingers which have laid yarn across the 80 needle circle.

10. A circular knitting machine having a circle of independent needles, means for raising the needles selectively, radially movable yarn fingers for laying a pattern yarn 90 in front of the needle or needles thus raised, said yarn fingers being of different length, in combination with an element having circumferential movement relatively to the needles and adapted temporarily to hold against said raised needles a pattern yarn 95 laid in front of the latter, and a stationary cam having circumferential movement relatively to the needles, having high and low points adapted to cooperate with the fingers 100 of different lengths to vary the lengths of time that the yarn fingers are held across the needle circle.

11. In a knitting machine having a circle of independent needles, means for raising needles selectively, pattern yarn fingers of 105 different length at their yarn feeding ends adapted to lay yarns across the needle circle for wrapping purposes and selecting butts at various levels on said fingers, in combination with a selector cam for said butts adapted to change butt levels between selections of the fingers; and means adjacent the needle circle adapted to maintain only the longer fingers across the circle after their 110 release by the selector cam.

12. In a circular knitting machine having a revolving circle of independent needles, means for raising needles selectively, yarn 115 fingers of different length adapted to lay wrapping yarns across the needle circle, and a vertically movable selector cam for said fingers, in combination with a cam outside the needle circle adapted to engage certain of said fingers and maintain them across the circle for varied lengths of travel after their 120 release by said selector cam.

13. In a circular knitting machine with selective needle wrapping means and needle selecting means governing the needles to be wrapped, the combination of a pattern drum 125 130

with peripheral patterning steps and governing means at the respective steps for selecting the needles to be wrapped, wrapping fingers, additional means at the respective steps 5 for selecting the fingers to be wrapped and means having movement relatively to the fingers for varying the wrapping effect of the fingers.

14. A circular knitting machine having 10 a rotary circle of independent needles, means for raising a selection of needles at a point on the needle circle different from the main yarn feed, a plurality of pattern yarn fingers whose feeding ends are of different lengths, and means tending to hold 15 the feeding ends of said fingers in non-laying position, in combination with selecting means adapted to cause the feeding ends of selected fingers to lay yarns across the needle 20 circle, and a maintaining cam having high and low points adapted to operate selectively on certain of the fingers chosen by the selecting means to give different lengths of dwell across the needle circle according to the number 25 of needles to be wrapped.

15. In a knitting machine having a circle of independent needles, means for raising needles selectively, pattern yarn fingers adapted to lay yarns across the needle circle 30 for wrapping purposes and selecting butts at various levels on said fingers, the yarn feeding ends of such fingers being of different lengths, in combination with a selector cam for said butts adapted to change 35 butt levels between selections of fingers, and means adjacent the needle circle adapted to select fingers according to the length of their yarn feeding ends and maintain them across the circle after their release by the selector 40 cam.

In testimony whereof we have signed our names to this specification.

ALBERT E. PAGE.

HARRY SWINGLEHURST, JR.
